UNITED STATES PATENT OFFICE

2,456,399

CATHODE-RAY APPARATUS

Richard B. Gethmann, Bridgeport, Conn., assignor to General Electric Company, a corporation of New York

Application October 24, 1945, Serial No. 624,275

7 Claims. (Cl. 250—161)

1

This invention relates to electron discharge devices of the cathode ray type and particularly to apparatus for controlling the direction and deflection of the electron beams of such devices.

Apparatus employing cathode ray tubes normally includes an arrangement for supporting the tube and for releasing it for servicing or replacement. During the manufacture of cathode ray tubes, relatively wide tolerances are permissible in the positioning of the elements of the electron gun and as a result the tubes do not produce their cathode ray beams in the same position and direction. It is therefore apparent that when one tube is substituted for another in the apparatus it becomes necessary to adjust the direction of the electron beam, and devices are commonly provided which make it possible to adjust the direction of the beam so that the spot on the fluorescent screen of the cathode ray tube appears at the desired position. However, an accurate display of the signal impressed on a cathode ray tube may be prevented because of undesirable deflection components of the magnetic field associated with the magnetic deflection and focus coils. The distortion of the signal due to these components can be minimized by bringing about a coincidence of the axes of the deflecting and focus coils and the axis of the electron beam. Accordingly it is an object of this invention to provide in an electron discharge apparatus of the cathode ray type an improved arrangement for mounting the deflecting coils and the focusing coil in their positions about the envelope of a cathode ray tube.

It is another object of this invention to provide an electron discharge apparatus of the cathode ray type including an improved arrangement for adjusting the position of the electron beam and for securing coincidence of the axes of the focusing and deflecting coils and of the beam.

The novel features which are believed to be characteristic of this invention are set forth with particularity in the appended claims. The invention itself, however, both as to its organization and method of operation, together with further objects and advantages thereof, may best be understood by reference to the following description taken in connection with the accompanying drawings in which Fig. 1 is a side elevation view, partly in section, of a cathode ray apparatus embodying this invention; Fig. 2 is an enlarged view, partly in section, of a portion of the apparatus shown in Fig. 1; Fig. 3 is a sectional view on the line 3—3 of Fig. 2; and Fig. 4 is a sectional view on the line 4—4 of Fig. 2.

2

Referring now to Fig. 1, a cathode ray tube 1 having a glass envelope comprising a bowl portion 2 and a neck portion 3 is mounted on a suitable supporting base indicated by the line 4 on a split collar 5 secured to a supporting member 6 and with the bowl portion held in a support 7 by an insulating collar 8 of rubber or other suitable resilient material. A glass viewing screen 9 is secured in the collar 8 so that it lies over the face of the cathode ray tube 1. A suitable housing 10 is mounted on the support 7 and encloses the bowl 2; this housing is also attached to the support 6 through adjusting rods 11. The cathode ray tube 1 is provided with suitable electrodes constituting an electron gun for projecting a cathode ray beam against a fluorescent screen covering the inner face of the bowl 2 adjacent the viewing screen 9. The details of construction of the elements of the electron gun are not essential to an understanding of this invention and have not been illustrated. However, a portion of the first anode of the electron gun is indicated at 12 in Fig. 2. In order to bring the electron beam to focus on the luminescent screen of the tube, a focusing coil 13 is mounted about the neck 3 of the tube between the anode 12, which is near the source of the electron beam, and a set of deflecting coils indicated at 14. The details of construction of the focusing coil 13 and of the deflecting coils 14 have not been shown, as these coils may be constructed in any suitable manner for providing magnetic fields for deflecting and for focusing the cathode ray beam. When the tube 1 is first placed in the supporting structure it is necessary to adjust the alignment of the cathode ray beam so that it is projected longitudinally of the neck 3 onto the screen in the desired direction. In order to adjust the direction of the electron beam there is provided an annular permanent magnet 15, which may be rotated about the neck 3 of the tube. This magnet is rotatably mounted on a nonmagnetic ring 16 which is clamped about an extended nonmagnetic sleeve 17 attached to the collar 5. The magnet 15 has a single air gap indicated at 18 and is so magnetized that it produces a field extending diametrically across the ring; thus, when the ring is rotated, the direction of the field is also rotated. It will be apparent that when the ring is rotated the direction of the electron beam is rotated. By rotating the ring 15 the beam may be moved through any angle into the desired position. In order to adjust the angle of the beam with respect to the longitudinal axis of the tube, the strength of the field produced by the magnet 15 is varied as well as the position of

the ring with respect to the anode 12. The change in the strength of the field is accomplished by adjusting the position of the magnetic ring longitudinally with respect to a cylindrical core 19 of magnetic material which is rigidly secured within the sleeve 17. The core 19 provides a short circuiting path for the flux produced by the ring 15, and a change in the position of the ring 15 with respect to the core 19 changes the amount of short circuited flux and thereby changes the flux density or strength of the field at the electron gun. The ring 16 which carries the magnetic ring 15 is clamped about the supporting sleeve 17 by a ring clamp 20 provided with a clamping thumb screw 21. The supporting ring 16 is provided with a plurality of longitudinal slots 22 extending from the seat of the magnet 15 through the right-hand edge of the support thereby forming a plurality of separate finger portions which may be clamped tightly about the sleeve 17. The supporting ring 16 may be clamped in any position on the sleeve 17 to select the position of the magnet 15 axially of the tube and with respect to the sleeve 19. The direction of the beam may also be adjusted by changing the longitudinal position of the cylinder 5 with respect to the anode 12 to effect a simultaneous change in the positions of the ring 15 and the core 19 with respect to the anode 12. One or more openings 23 may be provided in the sleeve 17 to afford a view of the position of the anode 12 of the tube when the ring and sleeve assembly is being adjusted with respect to the anode.

If the axis of the deflecting coil 13 and of the beam projected within the tube do not coincide, then variations in the focusing field result in distortion of the signal as it appears on the fluorescent screen. A similar situation prevails with respect to the deflecting coils 14, and it is desirable that the central axis of the deflecting coils and of the focusing coil coincide with the axis of the electron beam. In order to secure this result the deflecting and focusing coils are secured together on a common mounting collar 24 to provide a unitary assembly arranged so that the central magnetic axes of the coils are in alignment and extend in the direction in which the cathode ray beam is to be projected. The coils are spaced from the tube neck 3 and the collar 24 is attached to the supporting structure 6 by a mounting which permits adjustment of the collar 24 laterally of the tube neck 3 at right angles to the required axis of the beam. This mounting includes a mounting plate 25 which is supported on the structure 6 through the agency of an intermediate plate 26. The plate 25 is clamped to the collar 24 by turning set screws 27 shown in Fig. 3 until they press two split segments 28 formed on the plate 25 into engagement with the collar 24. As clearly shown in Fig. 3, the mounting plate 25 is slidably mounted with respect to the intermediate plate 26, it being provided with four horizontal slots 29 one at each corner of the plate 25 and which engage thumb screws 30 attached to the plate 26 for clamping the plates 25 and 26 together. Adjustment of the plate 25 with respect to the plate 26 is afforded by loosening the thumb screws 30 and then turning a thumb screw 31 mounted in lugs 32 and 33 on the plates 25 and 26, respectively. The plate 26 is slidably mounted on the supporting structure 6 in a manner similar to the mounting of the plate 25 just described, slots 34 being provided in the plate 26 and thumb screws 35 on the supporting structure 6. The plate 26 may be slidably moved with respect to

the supporting structure 6 by loosening the thumb screws 35 and then turning a thumb screw 36 mounted in lugs 37 and 38 on the plate 26 and support 6, respectively. The slots 29 are at right angles to the slots 34 and thus the position of the collar 24 and of the coils carried thereby may be adjusted laterally in any direction at right angles to the longitudinal axis of the tube neck 3. This lateral adjustment makes it possible to move the common central magnetic axis of the deflecting and focusing coils into any selected position; and since this axis extends in the direction in which the cathode ray beam is to be projected, the axes of the coils and of the beam may be brought into coincidence.

15 The focusing coil 13 is provided with a flanged boss or collar 39 which fits closely within the collar 24 and is secured thereto by a plurality of set screws 40. The focusing coil may be removed from the collar by loosening the set screws and 20 sliding the boss 39 out of the collar 24. This construction affords easy assembly of the focusing and deflecting coil unit, and the fit of the collar 39 within the collar 24 is such that alignment of 25 the axes of the focusing and deflecting coils is assured when the collar has been tightened in place by the set screws.

When a cathode ray tube is to be installed in the apparatus illustrated, the resilient collar 8, together with a metal frame structure indicated 30 at 41 and the glass screen 9, is fitted over the face of the bowl 2 of the tube. The tube is then inserted in the apparatus so that it rests on the lower portion of the support 5. As is clearly 35 shown in Fig. 4, the upper portion of the support 5 is removable from the lower portion by loosening two set screws 42 which are secured to the lower portion and enter slots 43 in the upper removable portion. Two pads 44 of rubber or other 40 suitable material are cemented to the upper and lower portions of the support 5. The upper portion of the clamp 5 is then placed over the neck of the tube, as shown in Fig. 4. The frame 41 is then secured in place on the support 5 so that 45 the face of the tube is in its desired position with the longitudinal axis of the neck of the tube substantially parallel to the axis of the deflecting and focusing unit. The tube is adjusted longitudinally of its support by means of rods 46 until the 50 gun 12 is in its required position as determined by sighting through one of the openings 23. The clamping screws 42 are then tightened to hold the upper portion of the clamping member 5 in position about the tube neck and thereby maintain 55 the tube in its desired position with respect to the magnetic ring 15. The electrical connections (not shown) are then made so that for purposes of testing there may be applied to the focusing coil either an alternating current or a direct current which can be switched to be negative, zero or positive. The tube is then excited to generate the electron beam and if the axis of the focus coil and the beam do not coincide a pattern will appear on the screen when alternating current is applied to the focus coil or the position of the beam will be shifted upon switching the direct current of the focus coil. This pattern or shifting of the beam is produced by a change in intensity and direction of the focusing field during each alternating current cycle or during each change in direction or intensity of the direct current. The pattern may be changed by rotating the magnetic ring 15 and by shifting it axially and also by shifting the position of the focusing 60 and deflecting coil unit. It will be found that

by adjustment of these devices the pattern produced by the beam may be reduced to a dot in the case of alternating testing current, and in the case of direct current the three dots corresponding to the three switching positions may be caused to coincide. This position of coincidence occurs when the direction of the beam is parallel to the axis of deflection of the focusing coil and coincidence therewith. Adjustment of the intensity of the field produced by the magnetic ring 15 may, of course, be made by axial movement of the core 19 during the adjustment. When the desired position for the magnetic ring on the tube 17 has been determined, the thumb screw 21 is tightened to maintain that position. In a similar manner the focusing and deflecting coil assembly is retained in its final desired position by tightening the thumb screws 30 and 35.

By constructing the supporting structure and the focusing and deflecting coils so that coincidence of the beam and coil axes may be secured, distortion of the signal portrayed on the screen is minimized. There is minimum astigmatism, and changes in the position of the spot resulting from random changes of focusing coil current are minimized. In cathode ray apparatus, utilizing the position of the luminescent spot on the screen as a measure of current, the coincidence of the coil and beam axes assures minimum error of the measurement.

While the invention has been illustrated in connection with a particular type of cathode ray tube, other applications and embodiments of the invention will readily be apparent to those skilled in the art. It is not, therefore, desired to limit the invention to the specific construction illustrated and described, and it is intended by the appended claims to cover all modifications which fall within the spirit and scope of the invention.

What I claim as new and desire to secure by Letters Patent of the United States is:

1. In an electron discharge apparatus of the cathode ray type including an envelope having therein a screen and an electron gun for projecting a cathode ray beam onto the screen, a magnetic focusing means arranged about the axis of the beam and having its central axis extending in the desired direction of the beam, means near the origin of the beam for adjusting the direction of the beam to make it parallel to the central axis of said focusing means, and means for moving said focusing means transversely of the direction of said beam for bringing the central axis of said focusing means into coincidence with the axis of said beam.

2. In an electron discharge apparatus of the cathode ray type including an envelope having therein a screen and an electron gun for projecting a cathode ray beam onto the screen, a magnetic focusing coil arranged about the axis of the beam and having its central axis extending in the desired direction of the beam, means providing a rotatable magnetic field about the beam near the origin thereof for adjusting the direction of the beam to make it parallel to the central axis of said focusing coil, and means for moving said coil transversely of the direction of said beam for bringing the central axis of said coil into coincidence with the axis of said beam.

3. In an electron discharge apparatus of the cathode ray type including an envelope having therein a screen and an electron gun for projecting a cathode ray beam onto the screen, a magnetic focusing means arranged about the axis of the beam and having its central axis extending

in the desired direction of the beam, a beam deflecting means arranged about said envelope between said focusing means and said screen, said deflecting means being fixed with respect to said focusing means and having its central axis in alignment with the central axis of said focusing means, means near the origin of the beam for adjusting the direction of the beam to make it parallel to the central axis of said focusing means, and means for moving said focusing and deflecting means transversely of the direction of said beam for bringing the central axis of said focusing and deflecting means into coincidence with the axis of said beam.

4. In an electron discharge apparatus of the cathode ray type including an envelope having therein a screen and an electron gun for projecting a cathode ray beam onto the screen, a magnetic focusing coil arranged about the axis of the beam and having its central axis extending in the desired direction of the beam, a deflecting coil assembly arranged about the axis of the beam between said focusing coil and said screen and having its central axis in alignment with the central axis of said focusing coil, said focusing and deflecting coils being secured together against relative movement therebetween, means providing a rotatable magnetic field about the beam near the origin thereof for adjusting the direction of the beam to make it parallel to the central axis of said focusing coil, and means for moving said focusing and deflecting coils transversely of the direction of said beam for bringing the central axis of said coils into coincidence with the axis of said beam.

5. In an electron discharge apparatus of the cathode ray type including an envelope having therein a screen and an electron gun for projecting a cathode ray onto the screen, a support for said envelope, a magnetic focusing coil and a magnetic deflecting coil secured together and having their central axes in alignment in the direction of the beam, means near the origin of the beam for adjusting the direction of the beam into parallelism with said central axes, and means for mounting said coils on said support and for affording movement of said coils together bodily laterally of the beam whereby the axis of said coils may be moved into coincidence with the axis of said beam.

6. In an electron discharge apparatus of the cathode ray type including an envelope having therein a screen and means for projecting a cathode ray beam onto the screen, means for supporting the envelope, a focusing and deflection coil unit surrounding the envelope and attached to the supporting structure, said unit being positioned with its central axis parallel to the desired axis of the cathode ray beam, means near the origin of the beam for adjusting the direction of the beam into parallelism with said central axis, and means affording movement of said unit laterally while maintaining said central axis in the same direction for moving said central axis into coincidence with the beam.

7. In an electron discharge apparatus of the cathode ray type including an envelope having therein a screen and means for projecting a cathode ray beam onto the screen, a supporting structure, a unitary assembly comprising a focusing coil and a deflecting coil having a common central axis, means near the origin of the beam for adjusting the direction of the beam into parallelism with said central axis, said assembly being

arranged to fit over the envelope in spaced relation thereto and with said common axis extending longitudinally within the envelope, a mounting plate attached to and extending transversely of said assembly, and means including a second plate for securing said assembly on said supporting structure for movement in any direction at right angles to said axis, said mounting plate being slidable in one direction on said second plate and said second plate being slidable with regard to said supporting structure at right angles to said one direction whereby said axis of said unit may be brought into coincidence with the cathode ray beam.
